JACK

Clarence S. Johnston, Amarillo, Tex.

Application January 9, 1940, Serial No. 313,106

6 Claims. (Cl. 254—111)

This invention relates to jacks, and has for one of its objects the production of a simple and efficient means for elevating the jack through the manipulation of an actuating handle.

Another object of this invention is the production of a jack which is so constructed as to allow the jack to be operated at high speed of two notches at a time, or adjusted for operation at low speed of one notch at a time.

A further object of this invention is the production of a simple and efficient means for controlling the lowering of the jack at the will of the operator.

Other objects and advantages of the present invention will be apparent throughout the following specification and claims.

In the drawings—

Figure 1 is a side elevational view of the jack, certain parts being shown in vertical section;

Figure 2 is a front elevational view of the jack, certain parts being shown in section;

Figure 3 is a vertical sectional view taken on line 3—3 of Figure 2;

Figure 4 is a transverse sectional view taken on line 4—4 of Figure 3;

Figure 5 is a transverse sectional view taken on line 5—5 of Figure 1;

Figure 6 is a vertical sectional view through a vehicle wheel showing the manner of using the jack for engaging a wheel and a second jack for supporting an axle;

Figure 7 is a side elevational view of the axle supporting jack;

Figure 8 is a vertical sectional view of a modified form of jack to that shown in Figure 3.

By referring to the drawings, it will be seen that 10 designates the base which supports a vertical tubular standard 11. This base 10 is provided with a vertical socket 12 preferably located at the center thereof, the inner end of the socket 12 being cone-shaped, as indicated at 13, for receiving the beveled or wedge-shaped end portion 14 of the standard 11. An auxiliary socket 15 is carried by the base 10 to one side of the socket 12, the socket 15 extending at an incline to the vertical axis of the base 10 and also being cone-shaped, as at 16, at its inner end.

The tubular standard 11 is provided with a plurality of teeth or notches 17 which are formed upon one side thereof, as illustrated in Figures 1, 2 and 3 of the drawings. The tubular standard 11 is adapted to receive the operating handle 18 which may be placed within the standard 11, as shown in Figure 1, and by forcing the handle 18 downwardly against the bottom of the socket 12, the base 10 may be easily detached from the tubular standard 11. The standard 11 will constitute an efficient case in which the handle 18 may be stored.

A lifting sleeve 19 is slidably mounted upon the standard 11 and is provided with a pair of spaced laterally extending flanges 20 between which flanges 20 is journaled an eccentric 21 upon a journal pin 22, the journal pin being fixed to the eccentric 21 and rotatably mounted through the flanges 20, as shown in Figure 4. One end of the journal pin 22 is fixed in any suitable manner to a shank 23 by being molded thereon, or otherwise secured, which shank 23 is adapted to receive the detachable operating handle 18 previously described.

A lifting latch 24 is carried by the eccentric 21 and the latch 24 is provided with a tooth-engaging end 25 which is adapted to engage the teeth or notches 17 of the standard 11, as shown. A retaining latch 26 is pivotally secured upon a journal pin 27 between the upper ends of the flanges 20, and this retaining latch 26 is also adapted to engage the teeth or notches 17 to retard downward movement of the teeth 17 upon the standard 11. This retaining latch 26 is provided with a rearwardly extending lug 28 which is adapted to be engaged by the end of the latch line 29 in a manner whereby the retaining latch 26 may be held out of engagement with the notches or teeth 17, as will be hereinafter described. This retaining latch 26 is provided with a laterally extending arm 30 near its lower end, which arm 30 extends through an arc-shaped slot 31 formed in one of the flanges 20 to facilitate the manual moving of the retaining latch 26 to and from an engaging position with respect to the notches or teeth 17.

35 A trigger plate 32 is journaled for rotating movement upon the journal pin 22 and is provided with an upstanding arm 33 which engages the laterally extending arm 30 of the retaining latch 26. This trigger plate 32 is also provided 40 with a shoulder 34 at its lower end, which shoulder is adapted to be engaged by a boss 35 carried by one side of the eccentric 21, the shoulder 34 being in the path of movement of the boss 35, as the eccentric 31 is rotated in a clockwise direction—note Figure 3. As the boss 35 is moved into engagement with the shoulder 34, the trigger plate 32 will be rotated to swing the arm 33 against the arm 30 and in this way kick or move the retaining latch 26 out of engagement with the notches or teeth 17 and causing the rearwardly extending lug 28 to engage the end of the latch spring 29, thereby holding the retaining latch 26 in an inoperative position or in the position shown in dotted lines in Figure 3. The lifting latch 24 is provided with an upstanding boss 36 on the top portion thereof and in a position to engage the arm 30 when the retaining latch 26 is in its dotted position whereby the movement of the handle 18 upwardly and toward

the upper end of the standard 11 will cause this boss 36 to contact the arm 30 moving the retaining latch 26 toward the standard 11 and disengaging the lug 28 from the spring latch 29.

A cam lever 37 is pivotally secured to the lifting latch 24, as shown in Figure 3, and engages a flat spring 38 carried by the latch 24 for moving this spring toward the transversely extending rivet 39 carried by the sleeve 19 and moving the latch laterally to the position shown in dotted lines in Figure 3 when the lever 37 is raised to the dotted position shown in Figure 3. When the lifting latch 24 is moved to its dotted position, the teeth engaging end 25 will be moved laterally or beyond the teeth or notches 17 of the standard 11 or to a position which would cause the end 25 of the lifting latch 24 to engage the tooth next below that shown in Figure 3, when the handle 18 is lowered and the eccentric 21 is rotated in a clockwise direction.

When the handle 18 is forced downwardly, the boss 35 will engage the shoulder 34, swinging the trigger plate 32 and causing the arm 33 to contact the arm 30 and move the retaining latch 26 into locking engagement with the latch spring 29. By manually swinging the lever 37 upwardly to the position shown in dotted lines in Figure 3, the spring 38 will be forced into contacting position shown in dotted lines in Figure 3, with the rivet 39. When the handle 18 is raised, the boss 36 on the top end of the lifting latch 24 will contact the arm 30 and force the retaining latch 26 out of locking engagement with the latch spring 29. The retaining latch 26 then drops into the next lower notch or tooth 17 on the standard 11, and the spring 38 will ride against the rivet 39 preventing the lifting latch 24 from dropping into the notch which it has just left, thereby causing the lower end 25 of the latch 24 to follow into the next lower notch 17. This action will cause the load to be stepped down one notch at a time. By manipulating the handle 18 as described above, it will be seen that the retaining latch 26 may be automatically moved to and from an operative as well as an inoperative position. A torsion spring 38' may be anchored at one end to the inner face of one of the flanges 20 and at the other end near the lower portion of the lifting latch 24, as shown in Figures 1 and 2 to normally urge the latch 24 into engagement with the standard 11. This spring 38' is preferably placed on the opposite side of the latch 24 with respect to the lever 37.

As shown, the sleeve 19 carries a lifting hook 40 at its upper end, which hook is supported upon suitable lugs 41 carried by the sleeve, and is retained against displacement by laterally bent ears 42 at the upper end of the sleeve 19. The lifting hook 40 is provided with laterally extending ears 43, the upper edges of which are formed on the arc of a circle, as indicated at 44, and are notched, as at 45, the lifting hook 40 and ears 43 being preferably shaped to conform to the contour of the hub of a wheel whereby the jack may be used in a manner as shown in Figure 6 hereinafter described.

By means of the jack mechanism illustrated and described, the handle 18 may be stepped-up two notches at a time for high speed. For low speed and power the retaining latch 26 is forced up as far as possible. The handle shank 23 is then raised to permit the lower latch to fall into the lower notch which increases the lifting power.

It should be understood that the jack is actuated by raising and lowering the handle 18 and

shank 23 in a pumping action and when a weight rests upon the lifting hook 40, the lifting latch 24 will force the sleeve 19 upwardly, as the handle 18 is lowered, and the retaining latch 26 will fall into the notches or teeth 17 and prevent the descent of the sleeve 19 upon the standard 11. When it is desired to permit the sleeve 19 to slide downwardly upon the standard and disengage the jack from the object which is being lifted, the handle 18 is forced downwardly to the point where the boss 35 contacts the shoulder 34 of the trigger member 32, and a further downward movement of the handle will cause the trigger member 32 to kick the retaining latch 26 out of engagement with the notches or teeth 17 and the lifting latch 24 will also be disengaged in this way permitting the sleeve 19 to slide downwardly to a disengaging position.

The jack may be used as a bumper jack in the conventional manner by having the lifting hook 40 engage a bumper, or the device may be used in the manner as illustrated in Figure 6, where the hook 40 may engage the wheel flange 46' of the wheel 46 or the outer end of the axle 47 for elevating the wheel to a desired position in the event the standard 11 is seated within the incised socket 15 of the base 10, as shown. When the wheel 46 is lifted to the position shown in Figure 6, I preferably employ a spring jack of the type shown in Figures 6 and 7, for engaging the axle after the wheel has been lifted to support the axle 47. The spring jack shown in detail in Figure 7 embodies a base 48 in which is slidably mounted a lifting shank 49 which is normally forced upwardly by means of an expansion spring 50 mounted within the base 48. The base 48 is preferably split as indicated at 51, the split portion being adapted to be drawn together by means of a bolt 52 which extends through the base and is engaged by a cam operating handle 53. By swinging the handle 53 downwardly the split portion of the base will be drawn tightly about the shank 49 and in this way hold the shank 49 in a set adjusted position to support the axle 47, at which time the hook 40 may be disengaged from the wheel flange 46' and the lifting jack removed so that the wheel 46 may be removed from the axle 47. Should it be desired any suitable adjustable support may be placed under the axle without departing from the spirit of the invention. The jack shown in Figure 7 and also Figure 6, for supporting the axle 47 may be released from the axle 47 by swinging the handle 53 upwardly and permitting the axle to assume its normal position after the wheel has been replaced.

In Figure 8 I have shown a modified form of the invention, wherein I employ a standard 11a upon which is slidably mounted a sleeve 19a somewhat similar to the sleeve 19. This sleeve 19a carries a pivotally mounted handle shank 23a which is pivoted, as at 22a upon a journal pin carried by the sleeve 19a. A friction brake shoe 54 is pivotally carried by a journal pin 55 at its upper end, the friction brake shoe also carrying a retaining latch 56 similar to the latch 26 for engaging the teeth or notches 17a of the standard 11a. A lifting latch 57 is pivotally secured, as at 58, to the handle shank 23a and a torsion spring 59 normally holds the lifting latch 57 in engagement with the notches or teeth 17a of the standard 11a. A trigger plate 60 is journaled upon the pin 22a and has an upwardly extending arm 61 which engages a laterally extending finger 62 of the retaining latch 56. A boss 63 is

formed upon the handle shank 23 and is adapted to engage the shoulder 64 at the bottom of the trigger 60 for swinging the trigger 60 and kicking the retaining latch 56 to a disengaging position as the handle shank 23a is moved in the direction of the arrow shown in Figure 8. A boss 65 is carried by the upper face of the shank 23a and is adapted to engage the arm 62 for moving the retaining latch 56 into a tooth-engaging position as the shank 23a is moved upwardly in the opposite direction to the arrow shown in Figure 8. A latching spring 66 similar to the spring 29 is adapted to engage the retaining latch 56 to hold the same in a disengaging position until released.

The lifting latch 57 may be swung outwardly from the shank 11a to a position where it will step-up a distance of two teeth at one operation, and this latch 57 may be moved to the position shown in dotted lines in Figure 8 by sliding the clip 67 upwardly to the position shown in dotted lines in Figure 8, thereby moving the flat spring 68 to the dotted line position which will cause the lifting latch 57 to be moved to the dotted line position shown in Figure 8. Figure 8 discloses a slightly modified form wherein the friction grip shoe 54 is employed and is actuated by the cam inner end 69 of the shank 23 and by means of this structure the friction shoe 54 will permit the sleeve 19a to slide downwardly and be controlled by the position of the handle shank 23a and the handle 18a. This friction grip shoe 54 is somewhat similar to the structure shown in my previous application for patent, Serial Number 246,691, filed December 19, 1938, patented April 9, 1940, as Patent No. 2,196,263, and operating in a manner similar to this structure so far as the cam and friction shoe are concerned.

It should be understood that certain detail changes in the mechanical construction and arrangement of parts may be employed without departing from the spirit of the invention so long as such changes fall within the scope of the appended claims.

Having described the invention, what is claimed is:

1. A jack of the class described comprising a standard, a sleeve having article lifting means, said sleeve being slidably mounted upon the standard, a retaining latch carried by the sleeve, the sleeve having means to be engaged by the retaining latch to hold the sleeve against descent, a lifting latch pivoted upon said sleeve and engaging the standard for moving the sleeve upwardly, an eccentric engaging the lifting latch, an operating handle for actuating the eccentric and elevating the sleeve as the operating handle is swung in one direction, means actuated by the eccentric for moving the retaining latch to an inoperative position when the operating handle is moved to one position, and means for engaging the retaining latch for moving the retaining latch to an operative position when the operating handle is moved to a second position.

2. A jack of the class described comprising a standard, a lifting sleeve slidably mounted upon the standard, a retaining latch adapted to engage the standard for holding the standard against descent, an eccentric pivotally mounted upon the sleeve, a lifting latch carried by the eccentric and adapted to engage the standard for elevating the sleeve as the eccentric is rotated, a handle for rotating the eccentric, a trigger pivotally mounted upon the sleeve, a boss carried by the eccentric for engaging the trig-

ger and swinging the same, and means carried by the retaining latch engageable by the trigger for swinging the retaining latch to a disengaging position.

5. A jack of the class described comprising a standard, a lifting sleeve slidably mounted upon the standard, a retaining latch adapted to engage the standard for holding the standard against descent, an eccentric pivotally mounted upon the sleeve, a lifting latch carried by the eccentric and adapted to engage the standard for elevating the sleeve as the eccentric is rotated, a handle for rotating the eccentric, a trigger pivotally mounted upon the sleeve, a boss carried by the eccentric for engaging the trigger and swinging the same, means carried by the retaining latch engageable by the trigger for swinging the retaining latch to a disengaging position, and a spring latch for engaging the retaining latch and detachably holding the retaining latch in an inoperative position.

4. A jack of the class described comprising a standard, a lifting sleeve slidably mounted upon the standard, a retaining latch adapted to engage the standard for holding the standard against descent, an eccentric pivotally mounted upon the sleeve, a lifting latch carried by the eccentric and adapted to engage the standard for elevating the sleeve as the eccentric is rotated, a handle for rotating the eccentric, a trigger pivotally mounted upon the sleeve, a boss carried by the eccentric for engaging the trigger and swinging the same, means carried by the retaining latch engageable by the trigger for swinging the retaining latch to a disengaging position, a spring latch for engaging the retaining latch and detachably holding the retaining latch in an inoperative position, and a boss carried by the lifting latch when the operating handle is moved to a selected position for releasing the retaining latch and moving the retaining latch to an operative position.

5. A jack of the class described comprising a standard, a lifting sleeve slidably mounted upon the standard, a retaining latch adapted to engage the standard for holding the standard against descent, an eccentric pivotally mounted upon the sleeve, a lifting latch carried by the eccentric and adapted to engage the standard for elevating the sleeve as the eccentric is rotated, a handle for rotating the eccentric, and means for shifting the position of the lifting latch upon the eccentric for regulating the distance of movement of the sleeve upon the standard at each operation of the handle.

6. A jack of the class described comprising a standard, a lifting sleeve slidably mounted upon the standard, a retaining latch adapted to engage the standard for holding the standard against descent, an eccentric pivotally mounted upon the sleeve, a lifting latch carried by the eccentric and adapted to engage the standard for elevating the sleeve as the eccentric is rotated, a handle for rotating the eccentric, a lever carried by the lifting latch, a spring carried by the lifting latch and shiftable laterally as the lever is swung to one position, an abutment carried by the sleeve and engageable by the spring for shifting the lifting latch laterally and moving the lifting latch upon the eccentric for regulating the distance of movement of the sleeve upon the standard as the handle is operated.
